ART OF CRACKING HYDROCARBONS

Application filed April 16, 1929. Serial No. 355,593.

This invention relates to improvements in the manufacture of lower boiling hydrocarbon oils, such as gasoline, from higher boiling hydrocarbon oils, such as gas oil, by pressure distillation cracking operations.

In carrying out the present invention, the raw oil, together with reflux condensate, is heated to a cracking temperature and the vapors of the cracked oil are subjected to a refluxing operation under superatmospheric pressure. Reflux condensate is discharged from the refluxing operation and the pressure on the discharged reflux condensate is reduced as it is discharged. Cool raw oil is introduced into the discharged reflux condensate as the pressure thereon is reduced and before any vapors formed by the pressure reduction are separated therefrom. The discharged reflux condensate is thus cooled to a temperature such that higher boiling components suitable to be supplied to the heating operation remain liquid and the raw oil is preheated by absorbing heat which might otherwise be absorbed in the vaporization of such higher boiling components on pressure reduction. Vapors of lower boiling components may be separated from the liquid mixture following the cooling operation. The resulting liquid mixture, including raw oil components and reflux condensate components, is supplied to the heating operation.

The separation of vapors of lower boiling components from the liquid mixture following the cooling operation may be carried out, for example, as described in application Serial No. 222,911, filed September 29, 1927, by Eugene C. Herthel.

The invention will be further described in connection with the accompanying drawing which illustrates diagrammatically and conventionally, in elevation and partly in section and with parts broken away, one form of apparatus adapted for carrying out the invention.

Referring to the drawing, a raw oil-reflux

condensate mixture is forced from the supply tank 1 through the heater 2 by means of the pump 3. The oil is heated to a cracking temperature in the heater 2 and the resulting hot oil products are discharged into the drum 4. In the drum 4, vapors and residual oil are separated; the vapors escape through the reflux tower 5 and the residual oil is discharged through connection 6. Reflux condensate flows from the reflux tower 5 to the supply tank 1 through connections 7 and 8. Vapors escape from the reflux tower 5 to the condenser 9 through connection 10.

The drum 4 and the reflux tower 5 are maintained under superatmospheric pressure by means of the valves 11, 12 and 13 in the connections 6, 7 and 10 respectively. Valve 13 is regulated to maintain and control the pressure in the drum 4 and the reflux tower 5. Valve 12 is regulated to control the discharge of reflux condensate from the reflux tower 5. Valve 11 is regulated to control the discharge of residual oil from the drum 4.

The heater 2 comprises a group of series connected heating tubes arranged in the heating flue of a heating furnace 14.

The condenser 9 is arranged to discharge into the receiver 15. The condensed distillate product is discharged from the receiver 15 through connection 16, uncondensed vapors and gases being discharged through connection 17.

The operation of the reflux tower 5 may be controlled by circulation of a cooling medium through the cooling coil 18, by the direct introduction of a part of the distillate product through connections 19 and 20 or of some similar fraction through connections 21 and 20 by means of pump 22, or by the direct introduction of a part of the raw oil supplied to the operation through connections 23 and 24 by means of pump 25, or by any of these means conjointly.

In carrying out this invention in the apparatus illustrated, cool raw oil is introduced

into the discharged reflux condensate flowing through connection 8 after passing through valve 12 through connection 26. The resulting mixture of reflux condensate and raw oil 5 is required to flow through connection 8 before any vapors formed by the pressure reduction on the discharged reflux condensate can separate from the oil mixture. This cool raw oil, introduced into the discharged 10 reflux condensate through connection 26, may be supplied through connection 27 by means of pump 25 or through connection 28 by means of pump 29. Higher boiling raw oil may be supplied by means of pump 29 and relatively 15 lower boiling raw oil may be supplied by means of pump 25, for example, or but a single raw stock may be supplied to the operation by means of pump 25. Any excess oil accumulating in the supply tank 1 may 20 be discharged through connection 30. Any vapors or gases separating in the supply tank 1 may be discharged through connection 31.

Drum 4, the reflux tower 5 and the supply tank 1 are with advantage lagged or thermally 25 insulated.

Lower boiling components, suitable as components of the distillate product for example, may be separated as vapors from the oil mixture in the supply tank 1 and discharged 30 through connection 31 to a suitable condenser or other recovery apparatus. Such lower boiling components may be components of reflux condensate formed in the reflux tower 5 or components of raw oil supplied through 35 connection 26 or through connection 24.

The following example of an operation embodying the invention as carried out in the apparatus illustrated will further illustrate the invention: Gas oil at a temperature of 40 60-80° F. is supplied through connections 28 and 26 by means of pump 29 at a rate sufficient to maintain the temperature of the oil mixture in the supply tank 1 below about 450° F. or better 350° F. The oil mixture 45 from the supply tank 1 is heated to a temperature approximating 850-950° F. as discharged from the heater 2. The cooling medium is circulated through the cooling coil 18 at a rate regulated so that vapors escape 50 from the reflux tower at a temperature in the neighborhood of 375-450° F. The drum 4 and the reflux tower 5 are maintained under a pressure in the neighborhood of 100-125 pounds per square inch, controlled by 55 the valve 13. A distillate including the gasoline product is collected in the receiver 15. It will be understood that the foregoing example is intended to illustrate the invention and that the invention is not limited to these 60 specific conditions of operation.

I claim:

In cracking higher boiling hydrocarbon oils to produce lower boiling hydrocarbon oils therefrom, the improvement which comprises 65 heating the oil to a cracking temperature and

subjecting vapors of the cracked oil to a refluxing operation under superatmospheric pressure, discharging reflux condensate from the refluxing operation into a vapor separating zone and reducing the pressure on the discharged reflux condensate, introducing cool oil into the discharged reflux condensate as the pressure is reduced thereon and before separation of any vapors formed by the pressure reduction in an amount sufficient 70 to reduce the temperature of the mixture to less than about 450° F., separately discharging vapors from said vapor separating zone and supplying the remaining liquid oil mixture to the heating operation.

In testimony whereof I affix my signature.
EDWARD W. ISOM.
